INVENTOR
Victor J. Evans
ATTORNEY

UNITED STATES PATENT OFFICE.

WILLIAM P. RHOADS, OF NEW BETHLEHEM, PENNSYLVANIA.

BRACKET.

Application filed May 19, 1922. Serial No. 562,176.

To all whom it may concern:

Be it known that I, WILLIAM P. RHOADS, a citizen of the United States, residing at New Bethlehem, in the county of Clarion and State of Pennsylvania, have invented new and useful Improvements in Brackets, of which the following is a specification.

This invention relates to a container and means for supporting the same, and more particularly to a tank and a supporting bracket therefor whereby the tank may be readily attached to a wash-tub or other supporting structure so as to be readily available for use.

One of the main objects of the invention is to provide a tank and a bracket therefor of the character stated of simple construction and operation which may be readily produced at small cost. A further object is to provide simple and efficient means whereby the bracket may be readily attached to or removed from the tank. Further objects will appear from the detailed description.

In the drawings:

Figure 1 is an end view of a tank with the bracket applied.

Figure 2 is a side view of the tank and bracket.

Figure 3 is a top plan view.

Figure 4 is a top plan view of a modified form of tank.

The bracket includes end frames 1 which are bent of sheet metal into substantially triangular shape, the horizontal arm 1^a of the frame being extended and folded back on itself to form an extension 1^b adapted to fit beneath the bottom of tank A. The extensions 1^b of the frames 1 are connected by a brace strip 2. The inner vertical arm 3 of each frame 1 projects above a brace strip 4 which is secured to arm 3 adjacent to the upper end thereof and to the upper end of the outer inclined arm 1^c of frame 1. The upper portion of arm 1^c is turned downwardly and outwardly to provide a hook element 1^d disposed substantially parallel with arm 1^c and adapted for engagement over a flat bar, the edge portion of a tub, or any other suitable supporting structure. The portion of arm 3 which projects above strip 4 forms an element 3^a which is adapted for engagement through a strap 5 secured to tank

A adjacent to the top thereof. The bracket constructed in the manner illustrated and described can be readily applied by inserting the elements 3^a into straps 5, the elements or projections 1^b of frames 1, and strip 2, fitting beneath the tank and co-operating with the straps 5 and elements 3^a for supporting it. When the bracket has been applied to the tank the tank may be readily attached to any suitable supporting structure over which the hooks 1^d are engaged so as to support the tank in position for use. In Figure 4 of the drawings the bracket shown is of the same construction as that illustrated in Figures 1, 2 and 3 but is illustrated as applied to a curved tank such as is sometimes used in laundry work.

What I claim is:

1. In a bracket of the character described, triangular frames having lower horizontal and inner vertical arms, the horizontal arms extending inwardly beyond the vertical arms, and inclined outer arms connecting the outer ends of the horizontal arms to the vertical arms below the upper ends thereof, and brace strips connecting said frames.

2. In a bracket of the character described, triangular frames having lower horizontal and inner vertical arms, the horizontal arms extending inwardly beyond the vertical arms, and inclined outer arms connecting the outer ends of the horizontal arms to the vertical arms below the upper ends thereof, and brace strips connecting said frames, the upper portions of the outer inclined arms of the frames being bent to form elements adapted for engagement with a supporting structure.

3. In a bracket of the character described, triangular frames having lower horizontal and inner vertical arms, the horizontal arms extending inwardly beyond the vertical arms, and inclined outer arms connecting the outer ends of the horizontal arms to the vertical arms below the upper ends thereof, and brace strips connecting said frames, the upper portions of the outer inclined arms of the frames being turned downwardly and outwardly to provide hook elements adapted for engagement over a supporting structure.

4. In a bracket of the character described, triangular frames each formed from a single strip of material and each including an inner

vertical arm, a lower horizontal arm, and an outer inclined brace arm extending from the outer end of the horizontal arm to the vertical arm adjacent to the upper end thereof, 5 said horizontal arm being extended inwardly beyond the lower end of the vertical arm; a brace strip secured through the extensions of

the brackets and connecting the same; and an upper brace strip, said upper strip and the vertical and inclined arms of the respective 10 brackets being all secured together.

In testimony whereof I affix my signature.

WILLIAM P. RHOADS.
